UNITED STATES PATENT OFFICE.

WILLIAM H. CLEMES, OF CLEVELAND, OHIO, ASSIGNOR TO THE TAYLOR & BOGGIS FOUNDRY COMPANY, OF SAME PLACE.

DESIGN FOR A WICK-TUBE AND BURNER-PLATE.

SPECIFICATION forming part of Design No. 21,442, dated March 29, 1892.

Application filed March 24, 1891. Serial No. 386,269. Term of patent 14 years.

To all whom it may concern:

Be it known that I, WILLIAM H. CLEMES, a citizen of the United States, and a resident of Cleveland, county of Cuyahoga, and State of Ohio, have invented and produced a new and original Design for Combined Wick-Tubes and Burner-Plates, of which the following is a specification, reference being had to the accompanying drawings, forming part thereof, 10 and in which—

Figure I represents a perspective view of an oblong wick-tube and burner-plate embodying my design; Fig. II, a side elevation, and Fig. III an end elevation.

15 The leading feature of my design consists in the downwardly-diverging outlines of the sides of the oblong wick-tube.

In the drawings the letter A indicates the oblong wick-tube and substantially horizontal outline for oblong burner-plate, the sides 20 of which have downwardly-diverging outlines, while its ends a' have outlines which

are at right angles, or nearly so, to the upper and lower edges of the tube. The lower ends of the outlines of the sides and ends merge 25 into the substantially horizontal outlines of the shoulder b of the oblong burner-plate B, and said horizontal lines pass into the vertical lines of the sides b'.

What I claim is—

30 A design for an oblong combined wick-tube and burner-plate, comprising the following outlines, viz: downwardly-diverging outlines for the sides of the oblong wick-tube and substantially horizontal outlines for the oblong 35 burner-plate, substantially as set forth.

In testimony that I claim the foregoing to be my invention I have hereunto set my hand this 20th day of March, A. D. 1891.

W. H. CLEMES.
